RAY McCARROLL, OF LA GRANDE, OREGON, ASSIGNOR OF FORTY-NINE PER CENT TO
L. W. WEEKS, OF LA GRANDE, OREGON

AIR HACKLING ATTACHMENT FOR SCUTCHING MACHINES

Application filed September 30, 1930. Serial No. 485,491.

This invention relates to an air hackling attachment for scutching machines, and has for its primary object to provide, in a manner as hereinafter set forth, an attachment 5 of such class by means of which fibers passing from the scutching blades of the machine may be hackled by air to remove loose particles from the fibers and to free the latter from kinks and snarls, thereby restoring 10 the fibers to substantially their original lengths and reducing to a minimum the damage done to the fibers in hackling the same. A further object of the invention is to provide an air hackling attachment of the character aforesaid by means of which fibers may be guided from scutching blades for the tips to scutching blades for the butts, thereby materially reducing the cost of hackling through elimination of waste and acceleration of output.

With the foregoing and other objects in view the invention consists of the novel construction, combination and arrangement of parts as hereinafter more particularly described, and as illustrated in the accompanying drawings wherein is shown an embodiment of the invention, but it is to be understood that the description and drawings are to be taken as illustrative, and that the invention is intended to be limited only by the scope of the claims hereunto appended.

In the accompanying drawings wherein like reference characters are employed to designate like parts throughout the several views:

Figure 1 is a longitudinal, vertical section through a scutching machine equipped with my attachment.

Figure 2 is an end elevation thereof.

Figure 3 is a transverse section taken at a point indicated by the line 3-3 of Figure 1.

Figure 4 is an enlarged fragmentary elevation of my attachment.

Figure 5 is a view similar to Figure 4 but taken at a right angle thereto.

Figure 6 is a section taken on the line 6-6 of Figure 4.

Referring to the drawings in detail, the numerals 1 and 2 respectively indicate a pair

of scutching chambers through which fibers, such as 3 are adapted to be passed. When passing through the chamber 1, the fibers 3 are suspended from a conveyor 4 with tips of the fibers hanging down, and are subjected 55 on opposite sides thereof to the action of a pair of scutching elements 5 and 6 extending longitudinally of the chamber 1 and journaled in the end walls 7 and 8 of the latter. The scutching elements 5 and 6 rotate in opposite directions, and each includes a plurality of radially projecting blades 9. The path of movement of the blades of the element 5 overlaps that of the blades of the element 6, and the elements 5 and 6 are synchronized in a manner to bring the blades of the element 5 into engagement with the fibers alternately with respect to the blades of the element 6. The blades 9 strike the fibers with a downward motion, thereby removing 70 from the fibers, broken straw, hurds, shives and the like.

From the chamber 1 the fibers are passed through an opening 8' in the end wall 8 to the chamber 2, wherein the fibers are suspended 75 from a conveyor 10 with the butts of the fibers hanging down and passing between scutching elements 11 journaled in the wall 8 common to the chambers 1 and 2, and the outer end wall 12' of the chamber 2. The 80 scutching elements 11 are similar to the scutching elements 5 and 6 and include blades 12. After passing between the elements 11, the fibers are delivered from the chamber 2 through an opening 13' in the wall 12'. Owing to the action of the blades 9, the tips 85 of the fibers have a tendency to snap upwardly when released by said blades, thereby kinking and snarling the fibers, whereby the length of many of the fibers normally would 90 be insufficient to reach the conveyor 10 before being released from the conveyor 4, consequently causing an enormous waste of fibers at the point of transfer from the chamber 1 to the chamber 2. Likewise the action of 95 the blades 12 have a tendency to kink and snarl the fibers when the latter are released from the blades 12. If such kinks and snarls are combed out mechanically, many of the fibers are broken, thereby causing a further 100

waste. By the employment of my attachment, the waste caused by the kinking of the fibers when released from the blades 9 and 12 is substantially eliminated.

5 The attachment includes an air pressure conduit 13 which is adapted for connection with a source of supply, such as a blower 14, or air compressor. Leading from the conduit 13 is a branch 15 with which is connected 10 a rotatably adjustable distributor indicated generally at 16. The distributor 16 includes a vertical trunk portion 17 which extends from the coupling 15 and is provided with a pair of oppositely extending, horizontally disposed branches 18 and 19 which extend 15 transversely of and project beyond conveyor 4. Slightly outwardly from a side edge of the conveyor 4, the branch 18 is formed with a downwardly extending continuation 20 which merges into a horizontally extending portion 21 disposed at a right angle to the branch 18. The portion 21 merges into a vertical portion 22 which terminates in a nozzle 23 having its outlet arranged in a manner to 25 discharge air onto the fibers at a downward inclination of substantially 45° and across the same at an angle of substantially 5° .

The branch 19 is provided with a vertical continuation 24, horizontal portion 25 and 30 vertical portion 26 similar to the corresponding portions of the branch 18. The portion 26 merges into a nozzle 27 having its outlet arranged in a manner to discharge air onto the fibers at a downward inclination of substantially 45° and across the same at an angle of substantially 10° . Owing to the angular relation with respect to each other of the streams of air being discharged onto the fibers, the latter will be combed by the air 35 to straighten the fibers and to remove hurdles and the like therefrom. Owing to the angular relation of the streams of air with respect to the direction of travel of the fibers, the tips of the latter will be actuated toward the conveyor 10 which grips the tips of the fibers just prior to the release of the butts of the fibers by the conveyor 4. Since the fibers will be extended at a downward and rearward inclination by the action of the air streams from 40 the nozzles 23 and 27, the conveyor 10 is located in a lower plane than the conveyor 4 and in spaced relation to the latter. The parts 17 to 23 of the distributor 16 are adjustably connected with respect to each other, and the 45 trunk portion 17 is adjustably connected with the branch 15 of the conduit 13.

In order that the fibers may have removed therefrom the kinks and snarls caused by the scutching blades 12 within the chamber 2, the 50 conduit 13 is provided with a second air distributor 28, which is the same in every respect as the distributor 16 and will not be specifically described, as the description of the distributor 16 also may be applied to the distributor 28. Owing to the action of the dis-

tributor 28, the fibers are delivered from the conveyor 10 in a straight and unbroken condition.

It is thought that the many advantages of an attachment in accordance with this invention will be readily apparent, and although the preferred embodiment of the invention is as illustrated and described, it is to be understood that changes in the size, shape and arrangement of parts may be resorted to, so long as such changes fall within the scope of the invention as defined in the appended claims.

What I claim is:—

1. In combination a scutching machine including a pair of oppositely disposed scutching elements for fiber tips, a conveyor for securing the butts of the fibers to pass the tips thereof between the scutching elements for said tips, a pair of scutching elements for the butts of the fibers, a conveyor for receiving the tips from the butt securing conveyor to pass the butts between the scutching elements for the butts, and a pair of air distributors for combing the fibers after the same have passed between said pairs of scutching elements respectively, each of said distributors including a pair of spaced nozzles having their outlets arranged to discharge air onto the fibers at an inclination lengthwise of the fibers and across the latter at an angle to the direction of travel of the fibers.

2. In combination of scutching machine including a pair of oppositely disposed scutching elements for fiber tips, a conveyor for securing the butts of the fibers to pass the tips thereof between the scutching elements for said tips, a pair of scutching elements for the butts of the fibers, a conveyor for receiving the tips from the butt securing conveyor to pass the butts between the scutching elements for the butts, and a pair of air distributors for combing the fibers after the same have passed between said pairs of scutching elements respectively, each of said distributors including a pair of spaced nozzles having their outlets arranged to discharge air onto the fibers at an inclination lengthwise of the fibers and across the latter at an angle to the direction of travel of the fibers, the air discharged from one of said nozzles of each pair being directed at a greater angle to the direction of travel of the fibers than the air from the other nozzle of such pair.

3. In combination, a scutching machine including a pair of oppositely disposed scutching elements for fiber tips, a conveyor for securing the butts of the fibers to pass the tips thereof between said scutching elements, a pair of oppositely disposed scutching elements for the butts of the fibers, a conveyor on a lower plane than the butt securing conveyor for receiving the tips from the butt securing conveyor to pass the butts between the scutching elements therefor, and an air dis-

tributor for combing the fibers after the same have passed the tip scutching elements, said distributor including a pair of spaced nozzles having their outlets arranged to discharge air onto the fibers at an inclination lengthwise thereof, the air from one of said nozzles further being discharged across the fibers at an angle to the direction of travel of the fibers to pass the tips of the latter to the tip receiving conveyor.

4. In a scutching machine, a pair of oppositely disposed scutching elements, means for passing vertically disposed fibers between the scutching elements, and an air distributor for combing the fibers after the same have passed the scutching elements, said air distributor including a pair of nozzles having their outlets arranged to discharge air onto the fibers at an inclination lengthwise thereof and across the same at an angle to the direction of travel of the fibers, the air discharged from one of said nozzles being directed at a greater angle to the direction of travel of the fibers than the air discharged from the other of said nozzles.

5. In a scutching machine, scutching mechanism for fiber tips, means for securing the butts of the fibers and for passing the tips thereof in position to be operated on by said scutching mechanism, scutching mechanism for the butts of the fibers, means for receiving the tips from the butt securing means and for passing the butts into position to be operated on by said scutching mechanism for the butts, and an air distributor for combing the fibers after the same have passed the tip scutching mechanism, said distributor including a pair of spaced nozzles having their outlets arranged to discharge air onto the fibers at an inclination lengthwise of the fibers and across the latter at an angle to the direction of travel of the fibers.

In testimony whereof, I affix my signature hereto.
